(57) **CLAIM**

The ornamental design for a re-bar clamp, as shown and described.

DESCRIPTION

FIG. 1 is a top perspective view of a re-bar clamp showing our new design;

FIG. 2 is a front elevational view thereof, the rear elevational view being identical;

FIG. 3 is a top plan view thereof;

FIG. 4 is a bottom plan view thereof;

FIG. 5 is a right side elevational view thereof, the left side elevational view being identical; and,

FIG. 6 is a front elevational view thereof.

The broken line showing of re-bar in FIGS. 1 and 6 is for illustrative purposes only and forms no part of the claimed design.
